[57] **CLAIM**

The ornamental design for a combined container and child-resistant closure, as shown and described.

DESCRIPTION

FIG. 1 is a perspective view of the present invention with the closure attached;

FIG. 2 is a top plan view with the closure attached;

FIG. 3 is a left side elevation view with the closure attached, which view is identical to a right side elevation view;

FIG. 4 is a top plan view of the container shown without the closure; and,

FIG. 5 is a front elevation of the container shown without the closure, the rear elevation is the same except for the continuous screw threading on the bottle neck.

The container is shown without the cap in FIGS 4 and 5 for clarity of illustration. The bottom of the container that is not shown in the drawings is flat and unornamented.
